DESIGN FOR A VACUUM CLEANER

Paul E. Frantz, Euclid, Ohio

Application July 19, 1940, Serial No. 93,783

Term of patent 7 years

To all whom it may concern:

Be it known that I, Paul E. Frantz, a citizen of the United States, residing at Euclid, in the county of Cuyahoga and State of Ohio, have invented a new, original, and ornamental Design for a Vacuum Cleaner, of which the following is a specification, reference being had to the accompanying drawing, forming a part thereof.

In the drawing: Figure 1 is a perspective view; Figure 2 is a side elevation, and Figure 3

is a top plan view of a vacuum cleaner showing my new design.

The characterizing feature of my design resides in the vacuum cleaner shown including a body portion tapering toward each end from substantially the medial portion thereof.

I claim:

The ornamental design for a vacuum cleaner, substantially as shown and described.

PAUL E. FRANTZ.
